ELECTRIC PROTECTION MEANS FOR LOOMS

William A. Blanchard, Millbury, Mass., assignor
to Crompton & Knowles Loom Works, Worcester, Mass., a corporation of Massachusetts

Application April 3, 1950, Serial No. 153,676

14 Claims. (Cl. 139—341)

1

This invention relates to improvements in electric protection means for looms of the type in which the shuttle if running properly gives indication of timely arrival at a given point along the lay and thereby permits continued loom operation.

It has been proposed heretofore to equip a loom with a type of electric protection utilizing a switch located along the lay between the shuttle boxes to have its condition changed by the shuttle. The switch is part of an electric circuit and if the shuttle changes the switch at a given time in the loom cycle the loom continues to operate, but if the switch is not changed at the given time the circuit controls stopping means to effect prompt stoppage of the loom.

In fast running looms the shuttle operated switch will be closed for only a very brief interval and it is desirable to provide some form of lock which will hold the switch momentarily in the position to which it is moved by the shuttle after the latter passes the switch. Such a lock will also permit continued loom operation if the shuttle should reach the switch earlier than normal. A lock for this purpose is shown for instance in co-pending application Serial No. 134,001, filed December 20, 1949 by Moss. It is necessary of course to restore the switch to its normal condition each beat of the loom in order that each flight of the shuttle may be detected, and this can be done in simple manner by a stop or the like on the loom frame to release the lock as the lay approaches front center.

Under some conditions of operation it is desirable to have two shuttle operated switches arranged in detecting zones spaced from each other along the lay between the shuttle boxes so that the shuttle will give indication of presence at a point between the longitudinal center of the lay and the shuttle box toward which it is traveling. When two switches are used both of them will ordinarily be closed by a single flight of the shuttle and when a switch lock is used the first of the switches to be closed will be temporarily locked and will not return to normal condition until the lay approaches front center. The second switch is not closed until some time later in the loom cycle and it is this second switch which is relied upon to determine whether or not the shuttle is running on time. If, therefore, closure of the first switch should be able to cause a change of energization of the loom controlling electromagnetic device, such as a relay or a solenoid, the operation of the second switch will be without effect.

In order that two switches may be employed

2

each having a locking feature it is an important object of the invention to arrange the switches in series so that even though the first switch to be closed is locked momentarily the controlling circuit cannot be closed until the second of the switches is also closed by the shuttle.

Electric protections of the type to which the invention more particularly relates can employ either of two loom controlling means. In one of these means a mechanically timed knock-off mechanism normally set to stop the loom can have its condition changed electromagnetically so that if the shuttle is running properly the normal setting will be canceled and the loom can continue to run. The other control means depends upon continuous energization of a relay which becomes deenergized with resultant loom stoppage if the shuttle is late.

It is a further object of the invention to utilize shuttle operated self-locking switches in series in either of these two loom control systems. When a normally deenergized solenoid is utilized to cancel the normal setting of a mechanical setting mechanism the two switches are arranged in series with the solenoid. When continuously energized relay is employed the two shuttle switches will be in series with each other but in a branch circuit which is in parallel with a timer branch circuit.

The invention further relates to improvements in the mechanism which enables the shuttle to operate its switch, this mechanism including preferably a normally stationary tube secured to the lay to provide a guide for a switch operating plunger moved relatively to the guide by the shuttle. The guide permits a relative adjustment between opposed forces exerted on the plunger so that the force required to be exerted by the shuttle on the plunger to close the switch may be reduced to a minimum. This adjustment also makes the mechanism adaptable to varying conditions of warp tension.

With these and other objects in view which will appear as the description proceeds, the invention resides in the combination and arrangement of parts hereinafter described and set forth.

In the accompanying drawings, wherein two forms of the invention are set forth,

Fig. 1 is a side elevation of a loom having the preferred form of the invention applied thereto.

Fig. 2 is an enlarged detail front elevation of one of the switch mechanisms looking in the direction of arrow 2, Fig. 1.

Fig. 3 is a vertical section on line 3—3, Fig. 2, showing the switch mechanism in its unlocking

55

position in full lines and in locked condition in dotted lines,

Fig. 4 is an enlarged detail horizontal section on line 4—4, Fig. 2,

Fig. 5 is an enlarged detailed vertical section on line 5—5, Fig. 3,

Fig. 6 is a diagrammatic view showing the preferred form of electric circuit used with the mechanical knock-off,

Fig. 7 is a view similar to Fig. 6 but showing the modified form of electric circuit used with the continuously energized relay,

Fig. 8 is a diagrammatic plan view of the lay showing the spaced shuttle detecting zones and the plungers which operate the shuttle switches located between the shuttle boxes at the ends of the lay, and

Fig. 9 is a detail side elevation showing part of the structure set forth in Fig. 1 adapted for use with the modified form of the invention.

Referring particularly to Fig. 1, wherein the preferred form of the invention is shown, a loom frame 1 supports top and bottom shafts 2 and 3, respectively, which in the present instance are connected by gears 4 and 5 which cause the bottom shaft to turn once for every second pick of the loom or rotation of shaft 2. The lay 6 is reciprocated backwardly and forwardly by connectors one of which is shown at 7 operated by the top or crank shaft 2. The shipper handle 8 is of usual form and has a depending arm 9 operatively connected to a rod 10 extending forwardly from a knock-off mechanism designated generally at 11. This mechanism includes a solenoid 12 mounted on a stationary support 13 and controlling a link 14 pivoted at its forward end to a knock-off lever 15. The latter is pivoted at its lower end to a stationary axis 16 which may be carried by the support or stand 13 and is connected at its upper end as at 17 to the rear end of rod 10.

An actuator or knock-off lever 18 is pivoted as at 19 to stand 13 and is oscillated every pick of the loom by two oppositely extending cams 20 and 21 secured to the bottom shaft. Ordinarily, the link 14 will be in the path of lever 18 to be moved by the latter to stop the loom, but when solenoid 12 is energized it will act to lift the link out of the path of the lever and as the latter rocks on a working stroke thereof it will miss link 14 and the loom will continue to run. If the solenoid is not energized before lever 18 starts its working stroke link 14 will be moved by the cam to stop the loom. As viewed in Fig. 1 the shipper handle for mechanism 8 is in the non-running position, but will be pulled forward, to the left in Fig. 1, in order to start loom operation. The knock-off mechanism may be similar to that shown in prior patent to Payne 1,873,465 except that in that patent the link 14 is normally out of the path of lever 18.

While the rod 10 has been described as being operatively connected to the handle 8 this is only one way in which forward motion of rod 10 can be utilized to stop the loom. The loom generally has a brake handle which is not shown herein, and in some instances the rod is connected to the brake handle. It is to be understood however that when rod 10 is moved forwardly from its normal running position mechanism will be set into operation to cause prompt loom stoppage. Lever 18 has its working stroke during each forward motion of the lay 6 so that the loom can be stopped at a time in its cycle when the

lay will be a considerable distance behind front center.

It is to be understood from the matter thus far described that the shuttle S will be picked during rearward motion of the lay at a time when the latter is approximately on its top center position, after which the shuttle will be in flight across the lay and will ordinarily come to rest at the opposite side of the loom during the ensuing forward motion of the lay. The shuttle passes through the top and bottom warp sheds W1 and W2, respectively, while in flight, and if the shuttle is running properly it will pass out of the warp shed while the lay is still some distance from its front center position, but if for any reason the shuttle is running slow it may not be able to get out of the shed in time to prevent a warp smash as the lay moves toward its front center position. It is under this last condition that the loom must be stopped in order to prevent a warp smash.

By referring to Fig. 8 it will be seen that the lay beam 30 having a shuttle race 31 has right and left shuttle boxes RB and LB, respectively, the shuttle passing from one shuttle box to the other shuttle box for each revolution of the top shaft 2. The lay has two shuttle detecting zones Z1 and Z2 and has right and left switch mechanisms designated generally at RS and LS for the zones Z1 and Z2, respectively. Each switch mechanism is located an appreciable distance from the adjacent shuttle box. These mechanisms are both alike and a detailed description will be given of but one of them, namely, switch mechanism RS.

Depending from and fixed with respect to the lay 6 is a hanger or support 32 bolted at 33 to the under side of beam 30. The hanger has a switch and plunger carrier 34 secured thereto as at 35, see Fig. 2. The shuttle operated switch RS is secured to the carrier 34 as at 36. This switch has a resilient blade 38 fastened at its left end, Fig. 3, to a post 39 fixed to the body 40 of the switch, which is preferably made of electric insulating material. The switch has a contact or electrode 41 normally spaced below but adapted for engagement with the blade 38.

Switch RS is equipped with a small plunger 43 vertically movable in the body 40 and having a shoulder 44 under an operating arm 45 pivoted as at 46 to the body 40. A spring 47 acts normally to hold the arm 45 in its raised position as shown in full lines in Fig. 3, and the blade 38 is resilient so that under these conditions it holds the small plunger 43 in raised position with its shoulder 44 against the arm 45.

A switch operating plunger 50 is arranged for vertical sliding motion on the lay and has the upper end 51 thereof normally projecting upwardly to a slight extent into the path of the shuttle and above the race plate 31. When the shuttle engages the upper end of the plunger the latter is depressed to move the arm 45 down from the full line position to the dotted line position shown in Fig. 3. This results in downward motion of the small plunger 43 which causes the blade 38 to engage contact 41 to close the switch.

In order that the shuttle switch RS may be held closed temporarily a lock is provided including a plunger 55 slidable in a forward extension 56 of the switch carrier 34. The plunger 55 is urged rearwardly by a compression spring 57 which surrounds part of a stem 58 extending forwardly from the plunger 55. A collar 59 secured to the forward end of stem 58, the left

end as viewed in Fig. 3, is adapted for engagement with the upper end of a release lever 60 pivoted as at 61 to the carrier 34. The lower end of lever 60 is adapted for engagement with a fixed but adjustable stop 62 held in any approved manner on the loom frame, as by a plate 63 depending from the breast beam 64 of the loom. As the lay approaches front center the lever 60 engages stop 62 and is rocked in a counter-clockwise direction as viewed in Fig. 3 to pull the plunger 55 forwardly.

Normally, the lever 45 and plunger 55 are as shown in full lines in Fig. 3, but when plunger 50 is depressed by the shuttle lever 45 moves down and the rear part of plunger 55 moves over it, as shown in dotted lines, Fig. 3, to lock the switch closed. This will generally occur when the lay is rearward of its front center position and resetting or release lever 60 is behind stop 62. When plunger 55 is moved forwardly at front center, as already described, the switch is unlocked and returns to its normal open position.

The shuttle operated plunger 50 passes through and is guided by a tube or guide 65 the lower end of which is threaded through a lateral extension 66 of the switch holder carrier 34. Nuts 67 and 68 are threaded on to the tube 65 above and below extension 66, respectively, to hold the tube in vertically adjusted position with respect to the lay. A compression spring 70 is interposed between the lower end of the tube 65 and a head 71 on the bottom of plunger 50. By varying the vertical position of the guide tube 65 with respect to the lay and switch the downward force exerted by spring 70 on the arm 45 can be adjusted. It will be apparent from Fig. 3 that the downward force derived from spring 70 is opposed by a greater upwardly directed force derived from spring 47. Adjustment of sleeve 65 permits variation of the force exerted by spring 70, and the nearer this force is to the force of spring 47 the less will be the force required from the shuttle to close switch RS.

As already stated, the two switches RS and LS and their associated parts will both be as described particularly in connection with Fig. 3, and the shuttle in a single flight across the loom will first depress the plunger 50 of one of these switch mechanisms and then the other. Each switch when depressed will be held by its lock until the lay reaches front center.

The electric circuit used with the preferred form of the invention is shown in Fig. 6. Considering that the shuttle is leaving the right box RB and is traveling across the loom in a left hand direction as viewed in Fig. 8, the shuttle will first pass through zone Z1 of the lay and close switch RS shortly after emerging from the shuttle box RB. It will then continue through the warp shed and pass through zone Z2, closing switch LS shortly before entering the left box LB. When both of these switches are closed the following loom protection electric circuit will be completed: transformer T, wire 75, switch LS, wire 76, switch RS, wire 77, solenoid 12, and wire 78 back to the transformer. If the shuttle is running on time switch LS will be closed and therefore the circuit will be completed to cause solenoid 12 to lift the link 14 just before the actuator or knock-off lever 18 starts a working stroke and the loom will continue to run. If, however, the shuttle should be late in arriving at switch LS and the latter should still be open when the working stroke of lever 18 starts, the link 14 will be pushed to the left, Figs. 1 and 6, to effect

loom stoppage. If the shuttle is running on time the lay will continue to front center in usual manner and both switches RS and LS will be unlocked so that the circuit of Fig. 6 will be in condition for another protection detecting operation on the next beat of the loom.

In the modified form of the invention the two branch circuit shown in Fig. 7 is utilized. During normal shuttle operation this circuit is normally closed by one or the other of its branches so that a relay 80 will be continuously energized. This relay controls a switch 81 associated with a control means C operating preferably electrically to stop the loom motor M, and hence the loom, when relay 80 becomes deenergized and switch 81 opens. The circuit shown in Fig. 7 includes a normally closed timer switch which will be set to open briefly when the shuttle passes the second of the switches RS or LS, provided the shuttle is on time.

In order to effect this timed opening of the switch TS the top shaft 2 as shown in Fig. 9 has a cam 82 secured thereto engaging an arm 83 of the switch mechanism TS. The latter has a blade 84 which normally engages a contact or electrode 85, see Fig. 7. At a given time in every one pick cycle of the loom cam 82 rocks arm 83 and switch TS will open at a time when the shuttle, if running on time, closes the second of the lay carried switches which it passes in a flight.

Normally, the following timer branch circuit will be closed: transformer T, wire 86, switch TS, wires 87 and 88, relay 80, and wire 89 back to the transformer. If the shuttle is running on time a second or shuttle detecting branch circuit will be closed as follows: transformer T1, wire 86, switch LS, wire 90, switch RS, wires 91 and 88, relay 80 and wire 89 back to the transformer. Relay 80 will therefore remain energized despite opening of switch TS. Should the shuttle be late, however, one of the switches RS or LS will be open when switch TS opens and the relay 80 will become deenergized. The switches RS and LS are the same as in the preferred form and will be connected in series in the second or shuttle detecting branch circuit just described. It will be understood from Fig. 7 that although the two switches RS and LS are connected in series with each other their branch detecting circuit is in parallel with the timer branch circuit.

Referring again to a left hand flight of the shuttle from box RB toward box LB, switch RS will be closed early in the shuttle flight while the timer switch is closed and the switch LS will be closed later when the timer switch is open, provided the shuttle is on time. When the shuttle travels in the reverse direction toward box RB switch RS will be closed after switch LS but during opening of switch TS, provided the shuttle is on time.

In the modified form of the invention the switches RS and LS will be unlocked when the lay reaches front center and will both move to open position, but at this time the switch TS is closed.

It will be obvious from both Figs. 6 and 7 that if the shuttle operated switches were in separate detecting branch circuits in parallel with the timer branch then closure of the first shuttle operated switch would energize the electromagnetic device when switch TS opened, and closure of the second lay carried switch would be of no effect. In both Figs. 6 and 7, however, the switches controlled by the shuttle are in series and both must

be closed and on time before the loom can continue to run.

In the operation of both forms of the invention it is to be understood that the stopping mechanism will act to stop the loom promptly at the time in the loom cycle when the shuttle should have closed both of the lay carried switches, and that this time is earlier in the forward beat of the lay than the point at which the locks for the switches are moved to unlocking position. The lay switches are locked until after the lever 18 has started its working stroke, or until after the timer switch TS closes after being opened by cam 82.

From the foregoing it will be seen that the invention sets forth an electric protection for a loom wherein two shuttle operated switches spaced along the lay may be held in locked position when operated by the shuttle and both switches must be closed by a given time in the loom cycle due to timely arrival of the shuttle at a given point along the length of the lay to permit continued loom operation. Both the shuttle operated switches will be opened by forward motion of the lay as the latter approaches front center. In both forms of the invention the shuttle operated switches are in series, being in series with the solenoid 12 in the preferred form of the invention, and being in series in a branch detector circuit which is in parallel to the timer circuit in the modified form of the invention. It will also be seen that the switches RS and LS are so made that adjustment of the sleeve 65 permits a variation in the force required by the shuttle to effect switch closure.

Having thus described the invention it will be seen that changes and modifications of the foregoing specific disclosure may be made without departing from the spirit and scope of the invention.

What is claimed as new is:

1. In electric protection means for a loom having a shuttle to travel across a lay, two normally open electric switches located at spaced points along the lay, lock means for each switch operative upon closure of the switch to hold the latter closed, the shuttle in a flight across the lay effecting closure first of one of said switches and then closure of the other switch, loom stopping means, electric circuit means including said switches in series controlling said stopping means and preventing the latter from stopping the loom if the shuttle effects closure of both of said switches by a given time in the loom cycle, and means operative subsequent to said time in the loom cycle to release said lock means to permit said switches to return to normal open position.

2. In electric protection means for a loom having a lay and a shuttle to move across the lay, two normally open electric switches on the lay located at spaced points therealong, lock means effective upon closure of either switch to hold the latter closed, the shuttle in a flight across the lay closing first one of said switches and then the other of said switches, loom stopping means, an electro-magnetic device controlling said stopping means, electric circuit means including said switches and said device in series operative to prevent said stopping means from stopping the loom if both of said switches have been closed by the shuttle at a given time in the loom cycle, and means releasing said lock means to effect opening of said switches at a point in the loom cycle subsequent to said given time.

3. In electric protection means for a loom hav-

ing a shuttle to travel along a lay having a shuttle box at each end thereof, two normally open electric switches on the lay between the shuttle boxes, one switch being adjacent to one of said shuttle boxes and the other switch being adjacent to the other shuttle box, the shuttle in a flight across the lay closing first one of said switches after leaving one of said shuttle boxes and thereafter closing the other switch before reaching the other shuttle box, means holding each switch closed subsequent to closure thereof, stopping means for the loom, an electro-magnetic device controlling said stopping means effective when energized at a given time in the loom cycle to prevent said stopping means from stopping the loom, electric circuit means including said switches and said device in series effective if both of said switches have been closed by the shuttle at said given time in the loom cycle to effect energization of said device at said time, and means cooperating with said holding means to effect opening of said switches subsequent to said given time in the loom cycle and prior to said given time in the next loom cycle.

4. In electric protection means for a loom having a lay across which a shuttle moves, two normally open switches located at spaced points along the lay, the shuttle in a flight across the lay closing first one of said switches and then closing the other switch, lock means operative upon closure of either switch to hold the latter closed, loom stopping means, an electromagnetic device controlling said stopping means effective if deenergized at a given time in the loom cycle to cause the stopping means to stop the loom but effective if energized at said given time to prevent said stopping means from stopping the loom, electric circuit means including said switches and said electromagnetic device in series effective when closed to energize said device, said circuit means being closed only upon closure of both of said switches by the shuttle, and means effecting release of the lock means at a point in the loom cycle subsequent to said given time.

5. In electric protection means for a loom having a lay across which a shuttle moves incident to loom operation, two normally open electric switches on the lay located at spaced points therealong, the shuttle when moving along the lay closing first one of said switches and then the other of said switches, lock means operative upon closure of said switches to hold the latter closed, stopping mechanism for the loom normally set to stop the loom at a given time in the loom cycle, an electromagnetic device controlling said stopping means and effective if energized at said time to prevent the stopping means from stopping the loom, electric circuit means including said device and said switches in series, said electric circuit being closed to energize said device at said given time if the shuttle in its movement along the lay effects closure of both of said switches by said given time, and means effecting release of said lock means at a point in the loom cycle subsequent to said given time.

6. In electric protection means for a loom having a lay provided with a shuttle box at each end thereof and in which a shuttle is in flight between said shuttle boxes for a portion of a one-pick cycle of the loom, two normally open electric switches on said lay between said shuttle boxes and spaced along the lay, one switch adjacent to one shuttle box and one switch adjacent to the other shuttle box, means operative upon closure of either switch to hold the latter closed, the

shuttle when in flight if running properly effecting closure of both of said switches by the time the loom has reached a given point in said one-pick cycle, loom stopping means normally operative to initiate loom stoppage at substantially said point in the cycle including a cam lever and a stopping element normally in the path of the cam lever, an electromagnetic device controlling the position of said element, and series electric circuit means including said switches and device effective to energize the latter to move the element out of the path of said cam lever if the shuttle in its flight between said shuttle boxes effects closure of both of said switches by the time the loom reaches said point in the cycle thereof.

7. In electric protection means for a loom having a lay provided with a shuttle box at each end thereof and a shuttle to move from one shuttle box along the lay to the other shuttle box, two normally open electric switches spaced along the lay effective when closed to remain closed until the lay reaches a given position in the forward movement thereof, whereupon said switches open if closed, loom stopping means normally operative to initiate loom stoppage at a given time in each one pick cycle of the loom before the lay reaches said given position, an electromagnetic device controlling said stopping means and effective if energized at said given time to prevent said stopping means from stopping the loom, and electric circuit means including said switches and device in series effective to energize said device if the shuttle while in flight between the shuttle boxes closes both of said switches not later than said time in the loom cycle.

8. In electric protection means for a loom having a lay provided with two detecting zones spaced along the length thereof and a shuttle which when traveling in one direction along the lay passes through one zone and then the other zone, the shuttle when traveling in the opposite direction passing first through said other zone and then through said one zone, the shuttle when running correctly on any flight thereof passing through the second zone through which it passes not later than a given time in the loom cycle, a normally open electric switch located at each zone effective when closed to remain closed until the lay reaches a given position in the forward movement thereof subsequent to said given time, whereupon said switch opens, loom stopping means normally operative to stop the loom at said given time in the loom cycle, electromagnetic means controlling said stopping means and effective if energized at said given time to prevent the stopping means from stopping the loom, and electric circuit means including said switches and said electromagnetic means in series energizing the latter and thereupon preventing the stop means from stopping the loom provided the shuttle has closed both of said switches not later than said given time in the loom cycle.

9. In electric protection means for a loom having a lay and a shuttle to move thereacross, two normally open electric switches on the lay located at spaced points along the length thereof, each switch when closed remaining closed until the lay reaches a given point in the forward movement thereof in the cycle of the loom, whereupon the switch opens, an electromagnetic device, stopping means dependent upon continued energization of said device to permit con-

tinued operation of the loom, said stopping means effective upon deenergization of the device to cause loom stoppage, a branch electric circuit including said device normally closed but open at a given time in the loom cycle prior to arrival of the lay at said point in the forward movement thereof, and other electric branch circuit means including said switches in series, said other branch circuit being in parallel with the first branch circuit means and effective to continue energization of said electromagnetic device if the shuttle in its flight across the lay has closed both of said switches by said given time in the loom cycle.

15 10. In electric loom protection for a loom having a lay and a shuttle to travel thereacross, two normally open electric switches located at spaced points along the lay, each switch when closed remaining closed until the lay reaches a given point in the forward movement thereof, whereupon the switch opens, an electromagnetic device, loom stopping means controlled by said device effective when the latter is energized to permit continued loom operation and effective when the device is deenergized to stop the loom, a branch electric circuit means including said device opening regularly at a given time in the loom cycle prior to arrival of the lay at said given point in the forward movement thereof, and a second branch electric circuit means including said switches in series, said second branch circuit being in parallel with the first branch circuit, and said second branch circuit effective to maintain said electromagnetic device energized upon opening of the first branch circuit means if both of said switches have been closed by the shuttle not later than said given time in the loom cycle.

11. In electric protection means for a loom having a lay and shuttle to move across the lay, an electromagnetic device, loom stopping means controlled by the device effective to permit continued loom operation if the device is energized and effective to stop loom operation if the device is deenergized, two branch electric circuits in parallel with each other, each branch when closed causing energization of the device, means opening one of said branches at a given time in the loom cycle, and two electric switches on the lay normally open but closed successively by the shuttle and arranged in series in the other branch circuit and effective if both switches are closed by the shuttle not later than said time in the loom cycle to continue energization of said device during the time the first branch circuit is open.

12. In electric protection means for a loom having a lay and a shuttle and dependent upon closure of an electric switch to permit continued loom operation, a plunger on the lay having a part thereof extending into the path of the shuttle and the latter when passing the plunger exerting a force thereon moving the plunger out of said path, said switch being normally open and mounted on the lay and exerting a second force on the plunger tending to move the latter into said path of the shuttle, a sleeve supported by the lay surrounding said plunger, a spring operatively interposed between the sleeve and the plunger exerting a third force on the plunger opposed to the second force, and means for adjusting the position of the sleeve relatively to the switch to vary the difference between said second and third forces and thereby permit adjustment 70 of the force required to be exerted by the shuttle

to cause the plunger to overcome the second force to effect closure of the switch.

13. In a lay for a loom operating with electric protection, a lay beam having a shuttle race, a plunger slideable vertically relatively to the beam and having the upper end thereof when in normal position extending above the race, a normally open electric switch supported by the lay operatively related to the lower end of the plunger and exerting an upward force on the latter tending to hold the upper end thereof in normal position, a sleeve surrounding the plunger supported by the beam, a spring operatively interposed between said sleeve and said plunger exerting a second force on the plunger opposing the force exerted by the switch, and means mounting the sleeve for adjustment on the lay in the direction of the length of the plunger to vary the force exerted by said spring against said force exerted by the switch.

14. In a lay for a loom operating with electric protection, a lay beam having a shuttle race, tubu-

10
15

5

lar member on the lay beam extending downwardly from the race, a plunger slideable within the tubular member having the upper end thereof above the race and tubular member, and an electric switch supported by the beam below the tubular member and the plunger and in position to be operated by the plunger when the latter moves downwardly within and relatively to the tubular member.
